UNITED STATES PATENT OFFICE.

EDWARD R. SARGENT, OF NEW HAVEN, CONNECTICUT, ASSIGNOR TO SARGENT & COMPANY, OF NEW HAVEN, CONNECTICUT, A CORPORATION OF CONNECTICUT.

CASKET-HANDLE.

1,390,461.

Specification of Letters Patent. Patented Sept. 13, 1921.

Application filed May 14, 1920. Serial No. 381,318.

To all whom it may concern:

Be it known that I, EDWARD R. SARGENT, a citizen of the United States, residing in the city of New Haven, State of Connecticut, 5 have invented certain new and useful Improvements in Casket-Handles, of which the following is a specification.

My invention relates to handles for caskets and the like, and more particularly to 10 that type of handles wherein a handle bar is supported by arms, of soft metal, pivoted to so-called socket plates.

One of the primary objects of my invention is to provide means for strengthening 15 the soft metal arms pivoted to the socket plates, and an improved means of attaching the strengthening brace to the soft arms.

A further object of my invention is to provide an improved strengthening means, 20 as described, of such a character that less of the soft metal need be employed, thereby effecting a great saving in the manufacture of these handles.

A third object of my invention is to provide 25 additional attaching means for attaching the handle bar to the pivoted arms.

To these and other ends, the invention consists in certain novel features and combinations of parts, to be hereinafter 30 described and claimed.

In the drawings, Figure 1 is a front elevation of a casket handle embodying my improvements the socket plates being omitted.

Fig. 2 is an enlarged detail rear elevation 35 of one of the arms and a portion of the handle.

Fig. 3 is a view in section on the line 3—3 of Fig. 2.

Fig. 4 is a detail sectional view on lines 40 4—4 of Fig. 3, or 4—4 of Fig. 6.

Fig. 5 is a rear view in elevation of an arm designed to be used with a bar circular in cross section and embodying my improvements.

Fig. 6 is a sectional view on line 6—6 of Fig. 5.

And Fig. 7 is a view similar to Fig. 3, but showing another form of fastening means.

In Fig. 1 of the drawings I have shown 50 my improvements as applied to a casket handle comprising a bar 10 polygonal in cross section; but it will be apparent that the shape of the bar is immaterial, as the invention may also be applied to handles comprising bars of other shapes. The bar 10 is sup-

ported from the side of the casket (not shown) by arms 11, pivoted in socket plates of usual form, as shown in the patent to Brooks, 1,167,044, Jan. 4, 1916, and in my Patent No. 1,164,220, Dec. 14, 1915. In the 60 present case these arms 11 comprise a soft metal portion 12, and a steel or hard metal brace or strengthening skeleton member 13. The soft metal portion is disposed on that side of the brace and arm, which is exposed 65 to view when in use, as shown in Fig. 1, thus giving the arm a pleasing and ornate appearance. In order, however, that the arm may be of the required strength, a great deal of metal had to be used therein, unless the 70 soft metal arm were reinforced by the hard metal brace 13. As will be apparent as this description proceeds, I have enabled to do away with practically all of this soft metal which is not exposed to view, and thereby 75 greatly lessen the cost of manufacture of the handles.

As shown in Fig. 3, the brace consists of a neck portion 14, extending up to the upper end of the arms 11, and an enlarged lower 80 portion 15, which is provided with the opening 16, to receive the bar 10. This hard metal brace is also provided with a lug 17 on the rear side of the opening 16, through which a screw 18 may be passed to secure 85 the bar 10 against movement in the arms 11. It will be understood, however, that, as shown in Fig. 7, a staple or nail 22 may be forced under the bar, wedging in between the base 19 of the soft metal arm and the 90 bar, and the bar thus secured against movement. This latter fastening means is described and claimed in the patent to Brooks heretofore referred to. Thus alternative fastening means for the bar are provided, 95 or both may be used at the same time if desired.

It is to be noted that the base portion of hard metal brace 13, which lies under the bar 10, is not of equal breadth with the 100 sides extending upwardly therefrom, but is partly cut away, as shown at 20, to provide for a thickness of soft metal 21 above the brace, thus more firmly securing the arm and brace together, and still providing for the 105 opening of the required size for the bar 10. The soft metal portion of the arm is cast about the brace, and by thus shaping the lower base of the brace, the soft metal flows in over the base and evenly fills the space 110

left by the portion which has been cut out. It is thus seen by reference to Figs. 2 and 3 that I have been enabled to dispense with the use of the soft metal except at the base 5 and front of the brace 13, and the provision of the lug 17 enables me to fasten the bar by a screw at the back without continuing the soft metal back of the brace, as is usually done for this purpose.

10 In Figs. 5 and 6 my improvements are shown as applied to an arm for the reception of a handle bar of circular cross section. The arm 11' comprises the soft metal portion 12' cast about the brace 13' in a manner similar to that previously described in connection with the polygonal bar. The base 13' comprises the neck 14' and the lower ring portion 15' provided with opening 16' for the reception of a round bar (not shown). The brace 13' is provided with a lug 17' for the reception of a screw to fasten the bar in the arm, and is cut away at 20' to allow a thickness of soft metal to flow over this brace as at 21' and lie between the brace and the handle bar. It is to be noted that in connection with the round handle, also, I have been enabled to dispense with a great deal more of the soft metal than has been possible in constructions 25 heretofore known and used.

It is, of course, not absolutely necessary to provide the cut out portions 20 and 20'. If desired, these may be omitted and the same thickness of hard metal left at all sides 35 of the openings 16 and 16', when the lugs 17 and 17' are provided. Moreover, the fastening lug 17 may be omitted from the structure shown in Figs. 5 and 6 and the bar secured to the arms by a wedge as shown 40 in my Patent No. 1,164,220 above referred to.

What I claim is:

1. In a casket handle, a handle bar, a supporting arm, comprising a soft metal ornamental portion and a strengthening brace, 45 said soft metal portion extending downwardly along the front of the brace then rearwardly along the lower portion of the brace and terminating at a point near the lower portion thereof.

2. In a casket handle, a supporting arm 50 comprising a soft metal ornamental exterior portion and a strengthening interior portion, said ornamental portion being entirely cut away from the inner side of said strengthening portion, a portion of said 55 brace being embedded in and surrounded by the soft metal of ornamental portion.

3. In a casket handle, a supporting arm comprising a soft metal exterior portion, a strengthening brace, therefor, at the rear 60 thereof, said soft metal being cut away from one side of said brace at the rear thereof, and securing means on said rear side of the brace, to secure the same to a handle bar.

4. In a casket handle, a supporting arm 65 and an arm brace provided with an opening therein, and a cut out portion communicating with said opening to provide for a more intimate connection between said arm and brace.

5. In a casket handle, a supporting arm and an arm brace provided with an opening therein, and a cut out portion communicating with said opening at the lower side thereof to provide for a more intimate connection 75 between said arm and brace.

6. In a casket handle, a handle bar and a supporting arm provided with an ornamental portion and a strengthening portion, a part of said strengthening portion being 80 wholly surrounded by and embedded in the ornamental portion, while another part remains exposed to engage the handle bar.

7. In a casket handle, a supporting arm comprising an ornamental portion and a 85 strengthening brace, a handle bar, said brace having an opening for the reception of said bar, and a cut out portion communicating with said opening.

8. In a casket handle, an arm comprising 90 a soft metal portion and a strengthening brace, a handle bar supported by said arm, and means, independent of said soft metal portion, for securing said bar against movement in said arm.

In witness whereof, I have hereunto set my hand on this 12th day of May, 1920.

EDWARD R. SARGENT.
